UNITED STATES PATENT OFFICE

132,604

DESIGN FOR A COMBINED TRAVELING AND CORRESPONDENCE CASE

Howard W. Russell, Collingswood, N. J.

Application November 12, 1941, Serial No. 104,121

Term of patent 14 years

To all whom it may concern:

Be it known that I, Howard W. Russell, a citizen of the United States, residing at Collingswood, in the county of Camden and State of New Jersey, have invented a new, original, and ornamental Design for a Combined Traveling and Correspondence Case, of which the following is a specification, reference being had to the accompanying drawing, forming part thereof.

In the drawing:

Fig. 1 is a perspective view of a combined traveling and correspondence case showing my new design, showing the same closed and viewed from the front thereof.

Fig. 2 is a similar view of the same, partly opened.

Fig. 3 is a similar view of the same from the rear and in a closed position.

I claim:

The ornamental design for a combined traveling and correspondence case, as shown.

HOWARD W. RUSSELL.
